LUBRICATING APPARATUS

Ernest W. Davis, Oak Park, Ill., assignor to Stewart-Warner Corporation, Chicago, Ill., a corporation of Virginia

Application September 18, 1937, Serial No. 164,463

3 Claims. (Cl. 221—100)

The invention relates to lubricating apparatus, and more particularly to lubricant dispensers.

One of the objects of the invention is to provide an improved lubricant dispenser, for distributing lubricant under pressure to various and sundry places.

Another object of the invention is to provide a low viscosity lubricant dispenser employing fluid under pressure, both to draw lubricant from a container by suction and to expel it under pressure to a point of dispensation.

Another object of the invention is to provide a portable dispenser for removing low viscosity lubricant by suction from a container and dispensing it by pressure under measuring conditions.

Another object of the invention is to provide an automatic means for preventing loss of lubricant from the dispenser when the dispenser is in unskilled hands or handled carelessly.

Another object of the invention is to provide an improved pneumatically operated lubricant dispenser having means for preventing intermixture of air and lubricant.

Another object of the invention is to provide a means preventing air from being present in a measured portion of lubricant being dispensed under pressure.

Another object of the invention is to provide a lubricant dispenser which is simple in construction and operation, effective in its use, and inexpensive to manufacture and maintain.

These being among the objects of the invention, other and further objects will become apparent from the drawings herein, the description relating thereto, and the appended claims, these and other objects being contemplated.

Fig. 1 of the drawings is a sectional view of a lubricant dispensing device illustrating a preferred embodiment of the invention;

Fig. 2 is an enlarged section of a portion of a lubricant dispensing device similar to, and illustrating structural modification of, the embodiment shown in Fig. 1;

Fig. 3 illustrates in section another modification of a portion of the invention; and

Fig. 4 is a section similar to Fig. 1 illustrating another embodiment of the invention.

Referring now to the drawings in further detail, a better understanding of the invention will be had when it is observed that the embodiment of the invention shown in Fig. 1 comprises, in general, an oil drum 10 supporting on the top 12 thereof a tank 14 which is exposed alternately to vacuum and pressure, so that oil is drawn by

suction from the drum 10 through the tube 16 and past the trap valve 18 when the tank 14 is subjected to the vacuum. The oil thus drawn into the tank 14 is expelled through the dispensing conduit 20 under pressure when the tank 14 is subjected to pressure.

More particularly, the tank 14 is made up of a vertically disposed cylindrical wall 22 closed at both ends by upper and lower heads 24 and 26, respectively, welded thereto as at 28, and provided with openings 30 and 32 therein. A hollow float 42 is slidably mounted on a vertical rod 44 within the tank 14 for movement between the openings 30 and 32, and carries on its upper and lower sides valve members 38 and 40 adapted respectively to close said openings, and the head constructions 24 and 26 around the openings being so formed as to provide valve seats 34 and 36, respectively, for the valve members mentioned. When the tank 14 is empty, the lower valve at 36 is closed during the time the tank 14 is subjected to atmospheric or super-atmospheric pressure, but is free to open to admit oil or air therethrough when the tank is at sub-atmospheric pressure. On the other hand, when the tank 14 is full, the upper valve at 34 is closed by the float during the time the tank is subjected to a partial vacuum, and is free to open to admit pressure fluid therethrough when pressure is applied at the opening 30. At all other times, both valves are open since the float 42 is supported at the lubricant level intermediate the two extremities described, and air accidentally present in the line 20 is free to pass to the top of the tank 14, keeping the lubricant dispensed free of air bubbles. Both valves have a large area so that they will respond to differential pressures applied to the opposite sides thereof and easily overcome any tendency to stick, which might otherwise occur if the device were idle for a substantial length of time.

The tank 14 is exposed to the vacuum and fluid pressure already mentioned by means of a conduit 50 leading from the opening 30 at the top of the tank 14 to the compartment 52 in the casing 60, which is located intermediate and exposed to the Venturi action of two spaced nozzles 54 and 56, as more particularly shown in Fig. 2. Both nozzles are threadedly supported in axial alignment in a threaded bore 58 extending through the body 60, and their spaced relation is determined by the shoulders 62 on each of them engaging sealing gaskets 64 disposed at each end of the bore 58 in slightly enlarged portions 66 thereof provided therefor in the body 60.

More particularly, one of the nozzles, nozzle 54, constitutes a concentration nozzle connected to a fluid pressure line 68 and provided with a passageway 70 therethrough leading from the line 68 as restricted at 72 providing a small orifice to a frusto-conical portion 74 widening towards the inner end of the nozzle. The second nozzle, nozzle 56, constitutes an expansion nozzle provided with a passageway 76 which is axially aligned with the portion 74 of the first nozzle and provided with a wide mouth 78 leading into another frusto-conical portion 80 which is an approximate continuation of the frusto-conical contour of the portion 74 in nozzle 54. A hand valve 82 is provided to control the flow of air through the expansion nozzle 56, which, when open, exhausts the expansion nozzle 56 to the atmosphere.

With the opening of the hand valve 82, a flow of air at high velocity is created through the frusto-conical passages 74 and 80 and the compartment 52. This flow creates in the compartment 52 the partial vacuum which is transmitted to the tank 14 through the conduit 50 as described. Then when the hand valve 82 is closed, the compartment 52, and in turn the tank 14, are exposed directly to the fluid pressure of the supply line 68 as supplied to the compartment by the nozzle 54. Consequently, with the closing and opening of the valve 82, the tank 14 can be subjected to vacuum or pressure at will.

The drum 10 is provided with a large central opening 84 and a small marginal opening 86 in the top 12 thereof which are bounded by bung rings 88 and 90, respectively, for closure and sealing purposes. A cover 92, fitting over and carried by the top 12 of the drum 10 is also provided with openings 94 and 96 corresponding to the openings in the top 12, and these openings have tubular inserts 98 and 100, which also extend downwardly into the drum. The insert 100 provides a convenient receptacle for the end of the discharge nozzle 102 when the compressor is not in use.

The suction tube 16 extends through the large openings 84 and 94, and being provided with an irregular opening 104 at the bottom end 106 thereof and resting against the bottom 108 of the drum 10 in a manner permitting the free admission of oil from the drum into the tube 16. The tube 16 is placed in the drum 10 by lowering it vertically through the insert 98 until the lower end 106 rests on the bottom 108 of the drum. In this connection, it is well to note that, preferably, the tube 16 is of such a length as to support on its upper end 110 the weight of the tank 14 and the parts associated therewith, free of any vertical support afforded by the cap 92 so that such weight may be transmitted directly to the bottom 108 and there borne by any agency supporting the drum 10.

To this end, namely the support of the tank 14 and its associated parts, the upper end 110 of the tube is provided with a radially flanged member 112, and in addition, the upper face of the flanged member 112 constitutes the seat element of the valve 18 and carries the valve elements 114 co-operable therewith. A casing 116 is carried on top of the flanged member 112 and the lower head construction 26 of the tank 14 is positioned on top of the casing 116. These three associated members are then secured together as an assembled unit, with suitable sealing gaskets 118 therebetween, by means of cap screws 120.

The casing 116 is provided with a central compartment 122 affording communication between the valve 18 and the openings 32 at the bottom of the tank 14. Upon one side of the casing 116, 5 is a threaded bore 124 which receives a rod 126 that supports the conduit 50 and associated nozzles 54 and 56, and upon the other side, the casing is provided with another threaded opening 128 leading from the compartment 122 and receiving 10 the discharge conduit 20, which in turn terminates in a hand control valve 130 having a nozzle 102 for conveying the lubricant forced from the tank 14 to the place where it is to be used.

From the description of the invention thus far, it will be observed that after a fresh drum 10 is opened and the cap 92 is placed on top thereof, the tube 16 carrying the tank 14 and associated parts is lowered to rest upon the bottom 108 of the drum 10, and the nozzle 54 is connected to the air pressure supply line 68. The valve 82 is then opened. This creates a partial vacuum in the tank 14, as described, of a sufficient degree to draw oil up through the tube 16 past the valves 18 and 36 and into the tank 14. As the tank 14 fills, the float 42 rises with the level of oil therein until such time as either the valve 82 may be closed, as at a desired calibrated graduation 48 on the gauge glass 46, or until the valve member 38 on top of the float is carried by the rising float against the seat 34 at the top of the tank 14. Thereafter, no further oil can be drawn from the drum 10, the tank 14 being fully charged, nor can oil escape from the tank 14 by means of any vacuum continuing to be present in the conduit 50 when the valve 82 is left open inadvertently, as sometimes it will be, for extended lengths of time. In this way, the tank 14 is filled completely with oil without any loss of lubricant.

Then, when the valve 82 is closed, the air pressure in the nozzle 54 is transmitted directly to the tank 14, as already described. The trap valve 18 will close if it has not already done so and the lubricant in the tank 14 will be discharged 40 through the compartment 122 and conduit 20 as controlled by the hand valve assembly 130 until such time as the float 42 drops to a position where the lower valve 40 thereon comes to rest against the valve seat 36 upon the top of the casing 116. At this point, there will be some oil left in the tank 14, which in conjunction with the closed valve 36 will prevent any air or froth from passing from the tank 14 into the dispensing conduit 20 to disrupt the empirical accuracy of the calibration of the gauge glass graduations. Thereafter, the above described cycle can be repeated at will by again opening the valve 82. The discharge of the tank 14 may, of course, be interrupted at any time by closure of the nozzle valve after the desired quantity of oil has been dispensed.

Fig. 2 illustrates a modification of the construction shown in Fig. 1 in which the conduit 50 is eliminated and the casing 60 supporting the nozzles 54 and 56 is welded directly on the tank 14 at the top thereof as a permanent part of the head construction 24.

In addition to this, the embodiment shown in Fig. 2 includes a float 42a made of buoyant material, such as cork, and the upper and lower surfaces have discs 132 cemented or otherwise secured thereto to serve as valve members for the purpose already described. Also, the casing 116 is modified slightly in form, as indicated at 116a, due to the fact that the rod 126

shown in Fig. 1 is no longer needed with this particular embodiment.

Fig. 3 illustrates a structural modification of the casing 116 and the tube 16. In this particular embodiment, the valve 114 is positioned at the bottom of the tube 16a in a suitable intake housing 134 secured at the lower end thereof, and the upper end of the tube 16a is threadedly received directly into the casing 116b as at 136, the casing 116b in turn supporting the tank 14 thereon by means of cap screws 120a, which hold together the lower head construction 26 and the casing 116b with a sealing gasket 138 therebetween. The passageway 140 leading from the compartment 122a of the casing 116b to the discharge conduit 20 is otherwise lengthened and the casing 116b conformed to provide a more compact assembly with the top 12 of the drum 10.

Referring to Fig. 4, the embodiment therein illustrated differs slightly from the embodiment illustrated in Fig. 2 in the following particulars. An insert 98a and suction tube 16b are permanently secured to the top 142 of a reservoir 144 in sealed relation as at 146, and a conduit 150 having a valve 148 interconnects the top 24 of the tank 14 and the top 142 of the reservoir 144. In addition to this, a hose 152 is connected to the reservoir, preferably at the top thereof, with its free end 154 adapted to be inserted into a large storage tank 156 of lubricant through an opening 158 in the top thereof.

The operation of this construction is such that given an empty tank 14 and reservoir 144, the hand valves 148 and 82 are then opened. The partial vacuum is established in the top of the tank as already explained and this vacuum is transmitted to the reservoir 144 through the pipe 150. This will draw oil from the storage tank 156 through the hose 152 into the reservoir 144 to fill the latter. In the event that the hand valves 82 and 148 are left open after the reservoir 144 and tank 14 are filled, the lubricant rising to the top 24 will raise the float 42a and close the valve 34, thus preventing the escape of lubricant.

When the valves 82 and 148 are closed, the air pressure operates as already described to discharge oil from the tank 14 into the dispensing conduit 20. Thereafter, the tank 14 can be emptied and replenished from the reservoir 144 without further attention to the valve 148 until such time as the reservoir is again empty. Then the sequence of operations already described can be repeated.

The drum 10 illustrated in Figs. 1 and 2 may be transported from place to place upon a wheeled cart 160, as controlled by the handle 162, or the reservoir 144 illustrated in Fig. 4 may be provided with swiveled wheels 164 connected at the bottom thereof for movement between the storage tank 156 and the places where lubricant is to be dispensed.

If desired, the gauge glass 46 may be omitted or disregarded in dispensing lubricant, and a suitable flow meter secured to the discharge conduit adjacent the nozzle 130, in a manner similar to that disclosed in the co-pending application of Joseph Bystricky, Serial No. 87,177, filed June 25, 1936. When the dispensing apparatus is thus equipped, the service station attendant may very quickly supply a measured quantity of lubricant to the crank case of an automobile or to any other lubricant receptacle, and he may do this without the necessity of carefully watching the gauge glass. Generally speaking, a lubricant flow meter of the type dis-

closed in the aforesaid application of Joseph Bystricky will serve as a more accurate and convenient meter than the gauge glass disclosed in this application as the means for metering the lubricant.

From the foregoing description, it will be appreciated that an improved lubricant dispensing device is provided in which compressed air is employed both to draw lubricant into a measuring device and to feed lubricant under pressure therefrom, in which loss of lubricant and intermixing of air with the lubricant is prevented, so that measuring of the lubricant will be accurate and waste will be prevented.

Although preferred embodiments of the invention are shown and described herein, it will be apparent to those skilled in the art that various and further modifications and changes may be made therein without departing from the spirit and substance of the invention, the scope of which is commensurate with the appended claims.

What is claimed is:

1. In a lubricant dispensing device, the combination of a lubricant metering chamber having a lubricant inlet and outlet at the lower end thereof and a pressure fluid inlet and outlet at the upper end thereof, a source of fluid under pressure, an ejector having its pressure inlet connected to said source and having its subatmospheric inlet connected to the top of said chamber, a manually operable valve in the exhaust passageway of said ejector to control discharge of pressure fluid from said ejector, and float controlled valve means responsive to the liquid level in said metering chamber to close said pressure fluid inlet and outlet at the upper end of said chamber when said chamber is substantially full of lubricant, and to close said combined inlet and outlet at the lower end of said chamber when the level of the lubricant in said chamber drops below a predetermined level.

2. In a lubricant dispensing apparatus, the combination of a lubricant reservoir, a lubricant measuring chamber, a conduit for conducting lubricant from said reservoir to said chamber, a check valve to prevent flow of lubricant from said chamber to said reservoir, a lubricant discharge conduit connected to the bottom of said measuring chamber, an ejector nozzle having its point of minimum pressure normally in communication with the upper end of said chamber, a source of air pressure connected to the inlet of said ejector nozzle, and a manually operable valve connected to the outlet of said ejector nozzle and effective when open to cause said chamber to be subjected to subatmospheric pressure and when closed to cause said chamber to be subjected to the pressure of said source.

3. A unitary lubricant dispensing apparatus adapted to dispense lubricant from original shipping containers comprising a lubricant measuring tank, a pipe secured to the lower end thereof and adapted to extend into the lubricant container to a point adjacent the bottom thereof, a check valve permitting flow of lubricant through said pipe from said container to said measuring tank but preventing flow of lubricant in the reverse direction, a discharge conduit connected to the lower end of said measuring tank, a valve at the free end of said discharge conduit for controlling the flow of lubricant from said conduit, an aspirating nozzle secured to the top of said tank and having its suction inlet connected to the upper end of said tank, means to supply air

under pressure to the pressure inlet of said aspirating nozzle, a manually operable valve to control the flow through the outlet of said aspirating nozzle, and float controlled valve means admitting flow of lubricant from said tank to said discharge conduit when the level of the

lubricant in said tank is above a predetermined minimum and to permit communication between said aspirating nozzle and said tank when the lubricant level in said tank is below a predetermined maximum height.

ERNEST W. DAVIS.
